UNITED STATES PATENT OFFICE.

GEORGE HERBERT BENTLEY, OF WESTMINSTER, LONDON, ENGLAND, ASSIGNOR OF
ONE-HALF TO EDMUND GARDNER APPLEBY, OF LONDON, ENGLAND.

GAS-GENERATOR.

1,153,417.

Specification of Letters Patent. Patented Sept. 14, 1915.

Application filed March 23, 1915. Serial No. 16,395.

To all whom it may concern:

Be it known that I, GEORGE HERBERT BENTLEY, a subject of the King of Great Britain, residing at 12 The Broadway, 5 Westminster, London, England, have invented new and useful Improvements in Gas-Generators, of which the following is a specification.

This invention has for its object the construction of a gas generator in which caking together of the fuels and also clinker formation is prevented and a large gasification secured. To effect this purpose the fuel in the generator is kept in continual motion by not only lifting and lowering the casing of the generator relatively to the grate, but also by simultaneously revolving the casing eccentrically around the grate. The grate also may be revolved in the opposite direction to the casing.

The casing, which may be circular or other desired shape, is carried by support and guide rings, the supporting rings being provided with cam shaped pieces at intervals to give the rising and falling motion. When operated by the driving gear the action is to rotate the fuel bed eccentrically around and against the fixed or rotating grate or air distributer and also to raise and lower the casing slightly during each revolution. This action prevents the formation of blow holes and clinker in the fuel bed, the formation of any clinker or caking mass on the walls, and by assisting the downward motion of the fuel bed the ashes are more readily removed. In some cases a stationary or revolving bar or "poker" is

fixed eccentrically to the casing in and near the top of the fuel bed.

The invention is applicable equally to 40 generators in which air is forced through the fuel bed by pressure on the one hand or drawn through by suction on the other.

Figure 1 is a plan (with the top removed) of a well known form of gas generator to 45 which this invention has been applied. Figs. 2 and 3 are sections on the lines 2—2 and 3—3, Fig. 1, the top being shown in place. Fig. 4 is a detached view of the rail.

a is the casing and *b* is the grate.

a' *a'* are rails fixed to the casing, these rails and the casing being supported and guided by rollers *c* *c'*.

a' is a ring of teeth fixed to the casing *a*.

d is a pinion gearing with the teeth *a'* 55 and having fixed to it a worn wheel *d'* driven by the worm *e*.

As shown at Fig. 4, the rails *a'* are cam shaped so that a rising and falling motion is given to the casing *a* as it revolves, and 60 the pinion *d* is made long enough to allow of this. As shown at Figs. 1 and 2, the casing *a* is eccentric to the grate *b*.

f is a revolving poker or stirrer.

What I claim is:—

The combination of a casing, a grate, means for lifting and lowering the casing relatively to the grate, and means for simultaneously revolving the casing eccentrically relatively to the grate.

GEORGE HERBERT BENTLEY.
